UNITED STATES PATENT OFFICE.

WALTER E. HOSCH, OF ST. LOUIS, MISSOURI; ANNIE MAE HOSCH, ADMINISTRATRIX OF SAID WALTER E. HOSCH, DECEASED, ASSIGNOR TO THE MEASUREGRAPH COMPANY, OF ST. LOUIS, MISSOURI, A CORPORATION.

CARRIAGE FOR COUNTER ATTACHMENTS.

1,336,231.

Specification of Letters Patent.

Patented Apr. 6, 1920.

Application filed November 15, 1917. Serial No. 202,134.

To all whom it may concern:

Be it known that I, WALTER E. HOSCH, a citizen of the United States, residing in the city of St. Louis and State of Missouri, have 5 invented new and useful Improvements in Carriages for Counter Attachments, of which the following is a specification.

This invention relates to store service apparatus, such as a salesman's accessory. The 10 apparatus to which I have described my invention as applied in the following specification, includes a cloth measuring instrument or machine which is mounted upon the counter so as to be within the convenient 15 reach of the salesman. This machine is mounted so that it may be moved along the counter to any point at which it is to be used. In the operation of the instrument the cloth, or other goods to be measured, is 20 pulled through the machine, usually in a direction parallel with the counter. The actuation of the mechanism of the machine by the cloth naturally generates considerable tension or pull in the cloth, and this 25 force would tend to pull the machine along the counter. The general object of this invention is to provide very simple and efficient means for supporting the measuring instrument on the counter, in such a way as 30 to permit the machine to be readily moved along the counter if sufficient force is applied to it but in such a way as to offer a sufficient resistance to prevent the machine being pulled along the counter by the cloth 35 when being measured. It is also an object to organize the parts in such a way that it is unnecessary to make adjustments to take up wear of the parts.

Further objects of the invention will appear hereinafter.

My pending application Serial No. 154,373 for improvements in counter attachments included a disclosure of means for effecting the objects of the present invention.

45 In the drawing which fully illustrates the preferred embodiment of my invention,

Figure 1 is a front elevation indicating a cloth measuring machine mounted on a carriage embodying my invention and showing 50 a portion of the track which operates to guide the carriage along the counter;

Fig. 2 is a rear elevation of a portion of the carriage, illustrating the manner in which the same operates. This view also

shows a portion of the track as viewed in section on the line 2—2 of Fig. 4;

Fig. 3 is a section taken on the line 3—3 of Fig. 2 and further illustrating the relation of the parts shown in Fig. 1;

Fig. 4 is a vertical section through the edge of the counter and through the track, and illustrating the manner in which the carriage is guided along the track;

Fig. 5 is a front elevation showing one of the track engaging members removed from the carriage; and

Fig. 6 is a plan of the parts shown in Fig. 5.

Fig. 7 is a view in rear elevation of a modified construction of carriage. 70

Referring more particularly to the parts, 1 represents a counter accessory of any kind, for example, a cloth measuring machine. This machine has a throat 2, through which the cloth is pulled in order to actuate the mechanism of the instrument, and indicates the length of the cloth and the price of the cloth at a dial (not shown) on the upper side of the instrument. The machine 1 is mounted on a pivot or stud 4 carried at the upper end of a post 5. In order to enable the height of the instrument to be adjusted, the post 5 slides through a guide sleeve 6, the side of said sleeve being provided with a sliding lock bolt 7, which enables the post to 85 be held at any desired height.

In applying my invention I provide a carriage comprising a bracket 8 which is preferably formed integral with the sleeve 6 and preferably elongated in a horizontal 90 direction. On this sleeve I provide movably mounted means for guiding the bracket along a track 9, said track preferably consisting of a pair of separated rails 10 and 11, which may be secured to the face of a back 95 rail 12 attached on the edge of the counter 13. (See Fig. 4.) And I also provide means for actuating this movably mounted means to hold the same in forcible engagement with the track. That is to say, I provide means for engaging the track at one point and additional means for engaging the track at another point along its length, and I provide means for constraining one, or both of these means so as to force the 105 same against the track. In this way the engaging means operates to guide the bracket along the track and also affords consider-

able resistance to the movement along the track. This resistance is sufficient to prevent the measuring machine from being pulled along the track by the cloth when being measured. In this connection, it should be understood that the machine 1 is movable on the pivot 4, so that it can be secured in a position at right angles to that in which it is shown in Fig. 1; in this latter position the cloth would be pulled through the throat 2, in a direction parallel with the rails 10 and 11.

In order to attain these results the movably mounted means referred to above, is preferably in the form of two members, or shoes 14, each shoe being pivotally attached to the side of the bracket on a suitable pivot bolt 15. On each pivot bolt 15 there is loosely mounted a roller 16, and each shoe 20 is also provided with a roller 17 which is attached at a point removed from the pivot point 15.

It will be seen that the roller 16 operates as means for engaging the track at one point 25 and the roller 17 operates as additional means to engage the track at another point along its length. However, it should be understood that this function of engaging the track at different points along its length 30 is not necessarily performed by a roller as these functions could be performed effectively by a shoe or block corresponding to the roller 16 and another shoe or block corresponding to the roller 17.

Associated with the members 14 I provide means for yieldingly moving them, that is to say rotating them on their pivots so as to hold the rollers 17 forcibly against the under side of the upper rail 10, and by 40 reason of the reaction exerted at this point the rollers 16 are forcibly pressed against the upper face of the lower rail 11. In other words the rollers 16 and 17 are held against the adjacent faces of the rails with such 45 force that they offer considerable resistance to the movement of the bracket along the track. The adjacent faces of the rails 10 and 11 have shallow curved grooves 18 formed in them, and these grooves receive the correspondingly rounded edges 19 of the rollers.

The bracket 8 is provided on its upper edge with a horizontal flange 20 directly over the upper edge of the shoes 14. This flange will permit a very limited rotary 55 movement of each shoe about its pivot, this rotary movement being sufficient to throw the rollers 16 and 17 of each shoe out of horizontal alignment. This separating of the rollers 16 and 17 in a vertical direction, of course, operates to hold them respectively 60 against the rails.

In order to provide a force tending to move the shoes in this way, and hold them yieldingly against the rails, I provide a coil 65 spring 21 which is associated with the shoes

in such a way that it tends to rotate them in the direction suggested. The coiled spring 21 is a tension spring and is attached at its ends to the extremities of arms 22 which project down from the under sides of 70 the shoes.

In order to guide the free edges of the shoes 14 I prefer to provide the bracket with a keeper plate 23, (see Figs. 2 and 3) which is attached by screws 23^a to a vertical 75 face 24 on the side of the sleeve; and the edges of this plate project over the ends of the shoes, being received in rabbet grooves 25, on the ends of the shoes. It should be understood, however, that the projecting 80 edges of the plate 23 do not fit tightly against the shoulders of the rabbet grooves in such a way as would prevent the free movement of the shoes.

In Fig. 2 the carriage is illustrated as in 85 the act of being introduced between the ends of the rails 10 and 11. In effecting this the rollers of one of the shoes are shoved between the rails and the carriage is then shoved along the rails until the rollers 17 90 and 16 of the unengaged shoe pass successively into the space between the rails.

The rollers 17 are secured on pivot screws 26 and the pivot bolts 15 have screw heads 27 which facilitate their attachment to the 95 shoe by means of suitable nuts 28 attached to their ends.

The rollers 16 and 17 are of slightly less diameter than the distance between the adjacent faces of the rails 10 and 11. But 100 this difference is very slight and only sufficient to give clearance, to enable each roller to rotate without engaging both rails simultaneously.

With the construction and organization 105 of parts described above, it is evident that the spring 21 tends to separate the rollers 17 and 16 in a vertical direction, forcing one set of rollers against one of the rails and the other set of rollers against the opposite rail. Under the action of this pressing force, the rollers offer considerable frictional resistance, although the carriage can be readily moved along the track by taking hold of it with sufficient force. It is evident 110 also that the spring 21 will operate to take up any wear of the rollers on their pivot pins and therefore it is unnecessary to make any adjustments to insure the continued forcible engagement with the rails after the parts 115 become worn from continued use.

A modified form of the invention is shown in Fig. 7, in which one of the track engaging members is guided to slide in a vertical direction and impelled to move in that direction by springs. Referring to this view, 120 28^a represents the bracket carrying a guide sleeve 29, and this bracket has a longitudinal flange 30 similar to the flange 20. Under 125 this flange and on the face of the bracket 130

28^a, I provide two fixed guide plates 31, 32 secured by screws 31^a, and between which a vertically movable shoe or plate 33 slides. This shoe is guided on the edges 34 and 35 of the guide plates. Between the edges 34 and 35 each guide plate 31 and 32 has a projecting tongue 36, and a similar tongue 37 is formed at each end of the shoe 33. These tongues 36 and 37 are provided with 10 alining pockets 38 which receive a spring 39 at each end of the shoe. The action of these springs is to force the shoe 33 upwardly so that its roller 40 tends to move out of line with the rollers 41 of the guide plates, and so that its roller will be pressed against the upper rail. The flange 30 limits the upward movement of the shoe 33 and prevents it from becoming displaced when the bracket is removed from the rails. In 20 order to hold the shoe on the face of the bracket 28^a, two screws 42 are provided passing through enlarged openings 43 which permit the free guiding of the shoe by the guide plates.

25 It is evident that by reason of the curved faces of the rollers and coöperating curved faces of the rails, the carriage will maintain its upright position although the weight of the carriage and the measuring instrument may be exerted out of line with the rollers.

30 It is understood that the embodiment of the invention described hereinabove is only one of the forms or embodiments my invention may take, and I do not wish to be limited in the practice of my invention nor in 35 my claims to the particular embodiment set forth.

What I claim is:—

1. In a counter attachment, the combination of a carriage adapted to move along a track, comprising a bracket, means movably mounted on said bracket for guiding the bracket along the track, additional means mounted on said bracket for engaging the track at another point along its length and also operating to guide the bracket along the track, both the said means operating to engage the track to resist the movement of the bracket along the track, and means for 45 actuating one of the aforesaid means to cause the same to normally engage the track.

2. In a counter attachment, the combination of a carriage adapted to move along a track, comprising a bracket, means movably mounted on said track for guiding the bracket along the track, additional means movably mounted on said bracket for engaging the track at another point along its length, both of said means coöperating to 55 guide the bracket along the track, and means

for actuating both the aforesaid means to cause the same to normally engage the track and offer a resistance to the movement of the bracket along the track.

3. In apparatus of the class described, a carriage adapted to move along a pair of rails, comprising a bracket, means movably mounted on said bracket for guiding the bracket along the rails and for yieldingly engaging the adjacent faces of the rails to 70 resist the movement of the bracket along the same, and a spring for actuating said means to force the same against the rails.

4. In apparatus of the class described, a carriage adapted to move along a pair of rails, comprising a bracket, a pair of members movably mounted on said bracket for guiding the bracket along the rails and for yieldingly engaging the adjacent faces of the rails to 80 resist the movement of the bracket along the same, and a spring associated with said members for forcing the same against the rails.

5. In apparatus of the class described, a carriage adapted to move along a pair of rails, comprising a bracket and pair of members pivotally mounted on said bracket, rollers carried thereby for engaging the adjacent faces of the rails, and a tension spring 85 for pulling said members toward each other and to hold the rollers in engagement with the adjacent faces of the rails.

6. In apparatus of the class described, a carriage adapted to move along a pair of rails, comprising a bracket, a pair of shoes 95 pivotally mounted respectively on said brackets, a roller carried by each shoe on its pivot for engaging one of the rails, and another roller carried by each shoe at a point removed from its pivot for engaging 100 the other rail, and a spring associated with said shoes tending to rotate the same on their pivots, and operating to maintain the rollers in forcible engagement with the adjacent faces of the rails.

7. In apparatus of the class described, a carriage adapted to coöperate with rails having grooves in their adjacent faces, said carriage comprising a bracket, rollers mounted on said bracket and having rounded 105 faces for engaging the grooves of the rails, and means for forcibly pressing said rollers against the faces of said grooves to support said bracket and offer a substantial resistance to the movement of the bracket 110 along the rails.

In testimony whereof I have hereunto set my hand.

WALTER E. HOSCH.
